UNITED STATES PATENT OFFICE.

ISIDORE ESKELL CLIFFORD, OF LONDON, COUNTY OF MIDDLESEX, ENGLAND.

APPARATUS FOR RECEIVING COINS AND RECEIPTING THEREFOR.

SPECIFICATION forming part of Letters Patent No. 414,795, dated November 12, 1889.

Application filed April 9, 1889. Serial No. 306,559. (No model.)

To all whom it may concern:

Be it known that I, ISIDORE ESKELL CLIFFORD, residing at London, in the county of Middlesex, England, a subject of the Queen of Great Britain and Ireland, have invented 5 certain new and useful Apparatus for Receiving Coin and Delivering a Receipt for Same; and I do hereby declare that the following is a full, clear, and exact description of the invention, which will enable others skilled in the art to which it appertains to make and use the same.

This invention has for its object to provide a novel bank whereby persons desiring to bank or deposit small sums—say a penny at 15 a time—can do so in a secure and convenient manner. The bank is so constructed and arranged that whenever a coin is dropped into it a receipt, check, or tally (hereinafter 20 called "receipt" only to avoid repetition) will be delivered to the depositor. On this receipt there will be marked any convenient sign or number, by which when it is presented at the proper office the officials will know what sum 25 has been deposited, and so be able to credit such amount to the person presenting the corresponding receipt.

The apparatus consists of mechanism so arranged that when a coin is deposited through 30 a suitable opening or slot it falls on or into a pivoted tray, where it is prevented from further movement by means of a stop or guard. On withdrawing a draw-plate which carries 35 said stop or guard the coin is released and falls into a hollow cylindrical receptacle or tube, wherein it remains until collected by some authorized person. This draw-plate has a slot or opening in it, which, when said draw-plate is pushed inward, comes beneath a correspondingly opening at the base of a column 40 containing a number of receipts, which are pressed downward by a weight. Consequently the lowermost receipt falls into the slot or opening, and when the draw-plate is pulled 45 out falls into a chute, whence it is taken by the depositor. The weight in the column containing the receipts bears some such indication as "Not in use," so that when it reaches the bottom of the column it will be visible 50 through a glazed opening provided for the purpose.

To prevent the withdrawal of the draw-

plate and delivery of a receipt before a coin has been introduced into the apparatus, there is a stud or nib projecting from the draw- 55 plate, which comes in the path of a hooked finger on the pivoted tray when no coin is resting on such tray; but so soon as a coin falls into the tray its weight is sufficient to cause the tray to turn on its fulcrum and to 60 thereby remove the hooked finger away from the path of the stud or nib on the draw-plate, thus enabling it to be withdrawn without hindrance.

The hollow cylindrical receptacle or tube 65 containing the deposited coins is removable, so that the order in which the coins fall into it is strictly retained. There is also a longitudinal slit cut in it for convenience of counting the coins. 70

The receipts are preferably numbered from No. 1 upward, and are so arranged that the first coin deposited will be acknowledged by No. 1 receipt. Likewise the second coin deposited will be acknowledged by No. 2 receipt, and so on. In this way should any person insert fraudulent deposits—such as disks of metal or bone, buttons, bad money, &c.—no inconvenience will occur, for, although a receipt will be delivered, it will bear a number 80 corresponding with such fraudulent deposit. For instance, say the tenth deposit is a fraudulent one, a receipt having "No. 10" inscribed thereon will be delivered; and if this receipt be tendered at the office it will at once 85 be canceled, or the depositor debited in case the amount should have been credited on presentation of the receipt and prior to the collection being made by the authorized official, because the officials will know upon examining the tube that the tenth deposit was 90 a fraudulent one.

In order that my invention may be readily understood, I proceed to describe the same, with reference to the accompanying drawings. 95

Figure 1 is a front elevation, Fig. 2 a plan, and Fig. 3 a side elevation, of a savings-bank constructed according to my invention. Fig. 4 is a vertical section taken on the line A B 100 of Fig. 2, showing the mechanism for conveying the coin to the cylindrical receptacle or tube. Fig. 5 is a vertical section on the line C D of Fig. 2, showing the manner in which

a receipt is delivered after insertion of a coin. Figs. 6, 6^a, and 6^b show detail views in plan, side view, and end view, respectively, of the guide or chute for delivering the receipt to the depositor. Figs. 7, 7^a, and 7^b show detail views in plan, side view, and end view, respectively, of the draw-plate. Figs. 8, 8^a, and 8^b show detail views in plan, side view, and rear elevation, respectively, of the hollow cylindrical tube into which the coins are finally received. Figs. 9, 9^a, and 9^b show detail views in front elevation, side elevation, and plan, respectively, of the pivoted tray or shoe. Figs. 10, 10^a, and 10^b show detail views in plan, front elevation, and side elevation, respectively, of the guide for conveying the coins into the pivoted tray or shoe. Figs. 11 and 11^x show a plan and edge view, respectively, of one form of receipt used.

20 *a* is the box or case of the apparatus, the interior being accessible by the door *b*.

c is a metal cover-plate, having secured firmly to it a column *e*, containing any desired number of receipts *d*, placed one above the other, as shown in Fig. 5. A weight *d'* tends to keep these receipts always pressed downward.

30 *e^x* is a glazed opening in the lower part of the column *e*, through which the weight *d*, with words inscribed on it indicating that the apparatus is no longer operative, may be seen when it reaches its lowest position. The plate *c* has an opening in it to permit of the receipts passing from the column *e* into the slot or opening *f'* in the draw-plate *f*.

35 Secured beneath the draw-plate is another plate *g*, having in it an opening *g'*, through which, when the draw-plate is withdrawn, carrying with it one of the receipts *d*, said receipt is able to fall into the chute or guide *g²*, along which it travels until it reaches the part *g³* outside the case, within easy reach of the depositor.

40 The receipt-column *e* is provided with a suitable swinging door *e'*, hinged at any point—as, for instance, at its top *e³*, Fig. 1—and the door *b* of the case *a* is provided with an attached angle-piece *b'*, adapted to bear at its inner end *b²* against the lower end of the door *e'* and hold the latter closed when the door *b* of the case *a* is closed, while if the door *b* is opened the door *e'* can also be opened, as will be understood by reference to the dotted lines, Fig. 1.

45 The coin to be deposited is dropped through the slot *i* in the cover-plate and falls into the chute *j*, which leads it on or into the pivoted shoe or tray *k*, where it is retained by the guard or stop *f^x*. When the draw-plate *f* is withdrawn, the guard *f^x* moves with it and so releases the coin, which immediately falls into the guide *m'*, and thence into the cylindrical column or tube *m*, wherein it is retained. The column *m* fits into a socket *m²*, from which it is easily removed when desired. There is a narrow longitudinal slit *m³*, extending almost the whole length of this tube, through which

the coins may be seen and easily counted, without disturbing their order, and false deposits discovered. The pivoted shoe or tray *k* has its fulcrum at *k'* on the cover-plate. It is provided with a hooked finger *k²*, which, when no coin is resting in the tray, comes in the path of a stud or nib *f²*, projecting from the draw-plate *f*, so that should any attempt be made to pull out this draw-plate the nib *f²* will engage with the hooked finger *k²*, and so lock the parts together and prevent further movement; but the weight of a coin resting in the tray is sufficient to overcome the balance-weight *k³* and to cause the tray to rock on its fulcrum into the position indicated by dotted lines in Fig. 4, thus removing the hooked finger from the path of the nib and allowing the draw-plate to be pulled out.

50 Having now described my invention, what I claim, and desire to secure by Letters Patent, is—

1. A savings-bank consisting of a case having a coin-depositing opening, a coin-receiving column in which the coins are received one upon the other in the order deposited in the coin-opening, a column containing superposed receipts corresponding with and marked to indicate the numerical order in which the deposits are made, and devices operative by the depositor for moving one of said receipts from the receipt-column and delivering it to the depositor after a coin has been deposited in the coin-opening, substantially as described.

2. A savings-bank consisting of a case having a coin-depositing opening, a coin-receiving column in which the coins are received one upon the other in the order deposited in the coin-opening, a column containing superposed receipts corresponding with and marked to indicate the numerical order in which the deposits are made, a chute receiving the coin from the coin-opening and conducting toward the upper end of the coin-column, a pendent swinging tray receiving the coin from the chute and located above the upper end of the coin-column, a draw-plate for moving a receipt from the receipt-column, and a pendent guard carried by and moving with the draw-plate for holding and releasing the coin resting in the swinging tray, substantially as described.

3. A savings-bank consisting of a case having a coin-opening, an external column *e*, an internal coin-receiver *m*, a stationary chute *j*, leading from the coin-opening, a pendent swinging tray *k*, receiving the coin from the chute and having a hooked finger *k²*, and a draw-plate having the slot *f'*, stud *f²*, and pendent guard *f^x*, for holding and releasing the coin resting in the swinging tray, substantially as described.

4. The combination, with a case having a cover-plate containing a coin-opening, of a column rising from the cover-plate, a coin-receiver inside the case, a chute leading from the coin-opening, a pendent swinging tray re-

ceiving the coin from the chute, a draw-plate having a slot and a pendent guard to hold and release the coin resting in the tray, a stationary plate arranged beneath the draw-plate 5 and having a slot, and a chute leading from the slot in the stationary plate to the exterior of the case, substantially as described.

5. The combination, with a case having a cover-plate containing a coin-opening, of a column above the cover-plate, a stationary chute leading from the coin-opening, a weighted swinging tray pivoted to the cover-plate and receiving the coin from the chute, and a draw-plate having an attached guard moving therewith to hold and release the coin resting in 10 the swinging tray, substantially as described.

6. The combination, with a case having a coin-opening, of a stationary chute leading from the coin-opening, a weighted swinging tray for receiving the coin from the chute, and 15 a sliding plate having an attached guard for holding and releasing the coin resting in the swinging tray, substantially as described.

In witness whereof I have signed my name in the presence of two subscribing witnesses.
